UNITED STATES PATENT OFFICE.

THOMAS S. WOODRUFF, OF GIRARD, PENNSYLVANIA, ASSIGNOR TO ROSA I. ODELL, OF NEW YORK, N. Y., AND SARAH H. WOODRUFF AND MARY W. JOHNSTON, OF ERIE, PENNSYLVANIA.

BICYCLE.

SPECIFICATION forming part of Letters Patent No. 628,426, dated July 4, 1899.

Application filed February 15, 1898. Serial No. 670,372. (No model.)

To all whom it may concern:

Be it known that I, THOMAS S. WOODRUFF, a citizen of the United States, residing at Girard, in the county of Erie and State of Pennsylvania, have invented certain new and useful Improvements in Bicycles; and I do hereby declare the following to be a full, clear, and exact description of the invention, such as will enable others skilled in the art to which it applies to make and use the same, reference being had to the accompanying drawings, and to the letters of reference marked thereon, forming part of this specification.

My invention relates to improvements in bicycles, and particularly to improvements in mechanism for applying hand-power to assist the ordinary foot-power in the propulsion thereof; and it consists substantially in securing the lower end of a vertical bar to the fork supporting the front wheel, said bar extending up in front of the frame supporting the handle-bar post and being connected by a backwardly-projecting arm to the top of the handle-post, so as to move freely therewith, and upon this vertical bar is secured a bearing for a sprocket-wheel, from which a chain extends down to a sprocket on the front wheel of the bicycle, and on the upper end of this vertical bar there is also a transverse sleeve in which the central portion of the handle-bar is pivoted, so as to rotate freely therein, and to the handle-bar rods are pivoted, which extend downward and forward to cranks on the sprocket-wheel mounted in the bearing on said bar, so that by moving the handle-bars up and down the sprocket-wheel is rotated.

Hereinafter my invention is more fully described and is illustrated in the accompanying drawings, in which—

Figure 1 is a side view in elevation of a portion of a bicycle embodying my invention. Fig. 2 is a side view in elevation of a portion of my device. Fig. 3 is a top or plan view of the handle-bar of my device.

In the drawings thus illustrating my invention, A is the front portion of a bicycle-frame provided with a sprocket-wheel B and foot-cranks b in the usual manner. The fork C, in which the front wheel D is journaled, is

mounted and secured in the vertical part A' of the bicycle-frame in the usual manner. To the fork C, above the wheel D, there is secured a forwardly-projecting arm c, and from the outer end of this arm c a tubular bar E extends upward in front of the part A' of the frame to and above the top thereof, where it is provided with an arm e, extending backward and curving downward until it enters the top of the handle-post F, where it is secured in the ordinary manner. By this means the bar E rotates freely around that part A' of the frame in unison with the handle-post therein, and in the top of the bar E, at its junction with the arm e thereon, there is a transverse sleeve-bearing G, adapted to receive the central part h' of a handle-bar H, which is so mounted thereon that it will rotate freely in the sleeve-bearing G. This sleeve-bearing G, I preferably make in two parts secured together by means of bolts g g.

Upon the front of the bar E, I clamp a transverse bearing I, in which is mounted the shaft J of a sprocket-wheel J', and upon the ends of the shaft J are cranks j, extending outward therefrom at the same angle, and from these cranks j connecting-rods K extend to the handle-bar H and have their ends pivoted in ears h h on the under side of the handle-bar, so that the movement of the handle-bar up and down in its bearing G operates through the connecting-rods K and the cranks j to rotate the sprocket-wheel J'. From the sprocket-wheel J' to a small sprocket d on the hub of the front wheel D there is a sprocket-chain L, by means whereof the rotation of the sprocket-wheel J' is conveyed to the wheel D.

I have thus shown and described convenient mechanism for utilizing my invention; but I do not confine myself to the exact forms and proportions herein shown and described, as

What I claim as new, and desire to secure by Letters Patent of the United States, is—

The combination, with a bicycle-frame, and steering-wheel; of a bar arranged parallel with the steering-head and provided at its upper part with an offset arm which engages with the said steering-head, an arm securing

the lower part of the said bar to the front fork, a sprocket-wheel carried by the said bar and provided with two crank-pins arranged in line with each other upon one side of its axis, a sprocket-wheel secured to the steering-wheel, a chain passing around the said sprocket-wheels, a rearwardly-projecting handle-bar having its middle portion pivoted to the top portion of the said bar, and connect-

ing-rod pivoted to the said handle-bar and engaging with the said crank-pins, substantially as set forth.

In testimony whereof, I affix my signature in presence of two witnesses.

THOMAS S. WOODRUFF.
